UNITED STATES PATENT OFFICE.

WILLIAM J. COURTNEY AND THOMAS F. COURTNEY, OF CHICAGO, ILLINOIS.

IMPLEMENT FOR SLITTING THE ENVELOP OF TWIN INSULATED WIRES.

No. 918,972.

Specification of Letters Patent.

Patented April 20, 1909.

Application filed July 31, 1908. Serial No. 446,217.

To all whom it may concern:

Be it known that we, WILLIAM J. COURTNEY and THOMAS F. COURTNEY, citizens of the United States, residing at Chicago, county of Cook, and State of Illinois, have invented certain new and useful Improvements in Implements for Slitting the Envelop of Twin Insulated Wires, of which the following is a specification.

10 This invention relates to implements in the nature of pliers especially intended for use by wire men in installing insulated wires, the object of the invention being to provide an implement of the character mentioned, 15 which is particularly designed to facilitate a quick and easy method of slitting the outer envelop or insulating coating of twin insulated wires prior to removing the same.

A further object of our invention is to provide an implement of a character as mentioned, which may be made to form an attachment for pliers of suitable design already in use, or which may be manufactured simultaneously with pliers especially designed to accommodate the same.

20 A still further object of our invention is to provide an implement which will be of the highest possible efficiency, and one which will be strong, durable, simple of construction, hence, of low cost to manufacture.

Other objects will appear hereinafter.

With these objects in view, our invention consists generally in a pair of pliers of novel construction, the upper jaw of the same being provided with a laterally extending blade-holding and wire-guiding member, and the lower jaw with a backing member upon which the twin insulated wires to be separated are adapted to rest during the process 40 of slitting the outer coating of the same.

Our invention further consists in a blade detachably mounted upon said blade holding member, said blade being adapted when twin wires are properly positioned upon said 45 backing member and the pliers drawn parallel with said wires, the jaws of the same being closed, to pierce and slit the insulating envelop of said wires so that it may be readily removed by the fingers.

50 Our invention further consists in certain details of construction and arrangements of parts all as will be hereinafter fully described and particularly pointed out in the claims.

Our invention will be more readily under-

stood by reference to the accompanying drawings forming a part of this specification, and in which,

Figure 1 is a perspective view of the preferred form of our device, Fig. 2 is a side elevation thereof, and Fig. 3 is a vertical transverse section of the same taken on the line x-x of Fig. 2.

Referring now to the drawings, 1 and 2 indicate the upper and lower jaws, respectively, of a pair of pliers which may be of any ordinary or preferred form, and 3 and 3' the respective handle portions thereof, 4 indicating the pin by which said jaws are hinged together. Suitably secured as by soldering or by screws, the latter being used in the attachment form 70 of our device, to one side of the jaw 1 and laterally extending therefrom, is a channel-shaped member 5, the channel 6 formed by the depending ears 7 of said member 5 being longitudinally extending, that is, parallel 75 with the sides of said jaws. Detachably secured as by a screw 8, so as to facilitate sharpening or renewing of the same, to said member 5, the same preferably resting in a recess 9 provided for the reception thereof, 80 is the shank 10 of a downwardly extending, preferably tool steel, blade 11. Said blade shank 10 is so positioned upon said member 5 that the blade-edge 12 of the depending blade 11 thereof extends substantially centrally and vertically in said channel 6 for reasons hereinafter stated. Suitably secured as by soldering or by screws, the latter being preferably used in the attachment form of our device, to the side of the jaw 3 and laterally extending therefrom, the same being positioned directly below the member 5 and blade 11, is an angular member 13, the horizontally extending portion 14 of said member 13 being adapted to act as a backing or 90 support for wires during the process of removing the envelop of the same.

In using the device, the jaws of the pliers are first opened, the twin wires to be separated being placed upon the support or backing 100 14 whereupon the jaws are closed. It is obvious that as the plier jaws are closed as mentioned, the blade 11 by reason of its being positioned centrally in the channel 6, will pierce the envelop of the twin wire necessarily resting between the wire members of said twin wire. By drawing the pliers backwardly to the end of the wire, one side of the

envelop will be slit, as clearly shown in Fig. 1 of the accompanying drawings, and by reversing the wire the opposite side of the envelop of the same may also be slit, whereupon said envelop may readily be removed by the fingers. By the provision of the device as just described in a pair of pliers, it will obviously facilitate means for easily, quickly and efficiently removing an insulating envelop or other coating of twin wires without danger of disturbing the insulating covering of the separate twin wire members, and will obviate the usual method of separating wires which is generally done with a knife blade or other like tool, in which case the insulation of the separate wires is almost invariably cut and bruised, making it necessary to supply other insulation for the same, thus resulting in a waste of time and labor, hence a financial loss.

In our preferred form of pliers, for the purpose of severing or actually cutting the wire, we provide each of the jaws of said pliers with a cutting or knife-edge 15, the latter constituting a wire clipper, and recess each jaw beyond said knife-edge as at 16 for obvious reasons. Said clipper is not an important feature in our invention however, but we show the same in order to illustrate a handy tool of which our invention is the central and main part.

Having described our invention what we

claim as new, and desire to secure by Letters Patent, is:

1. An implement of the character described comprising two members hinged together, a supporting plate projecting to one side of one of said members, a channel-shaped guide secured to the side of the other member and located opposite to the said plate, a cutting blade disposed beside the channel-shaped guide at the center thereof, and a shank on said blade secured to the outer face of said channel-shaped guide.

2. An implement of the character described comprising two members hinged together, a supporting plate projecting to one side of one of said members, a channel-shaped guide projecting to the same side of the other member and located above the plate, and having a recess in its outer face, a blade shank secured in the recess of the guide, and a blade on said shank located at the center of the guide and projecting down beside the same.

In testimony whereof we have signed our names to this specification in the presence of two subscribing witnesses.

WILLIAM J. COURTNEY.
THOMAS F. COURTNEY.
